SOFA BED

Daniel F. Caldemeyer, Evansville, Ind.

Application August 17, 1956, Serial No. 42,648

Term of patent 14 years

(Cl. D15—11)

The figure is a perspective view of my sofa bed.

The rear of the sofa bed is plain. The characteristic features of the design reside in the portions shown by means of full lines in the drawing.

I claim:

The ornamental design for a sofa bed, as shown and described.
